Application October 19, 1953, Serial No. 386,862

12 Claims. (Cl. 316—26)

The present invention relates to electro-mechanical transducers, and more particularly to transducers adapted to convert sound vibrations into alternating voltage and alternating voltage into sound vibrations.

Vibration transducers of the present type have many applications, a principal one being in a motion indicating system wherein movement in a protected room or enclosure is detected. This system employs a transducer used as a loud speaker or transmitter to emit vibrations, preferably above the audible range. These vibration waves reflect about an enclosed area and impinge upon another transducer arranged as a microphone or receiver. Because of the Doppler effect, any substantial movement within the area will cause a variation in the frequency of the vibrational energy detected by the receiving transducer whereby a signaling device may be actuated to indicate an intruder in the protected room.

The effectiveness of the above system depends in part upon effectively filling the room with paths of vibrational energy. While conventional microphones and loud speakers have been used with a certain amount of success, these devices have certain inherent drawbacks that limit maximum efficiency and sensitivity of the system. For example, the diaphragm of a loud speaker has a relatively small area and sound waves emanating therefrom are generally directed to take a definite path rather than being permitted to radiate out in all directions as would be desirable in a motion detecting system. Likewise, the conventional microphone is similarly limited to receiving vibrations from definite directions rather than from substantially all directions. A conventional loud speaker in a motion detecting system will radiate vibration waves which will reflect about the protected area and eventually reach the microphone. However, due to the directional limitations of such transducers, the number of reflections will be exceedingly large and hence the efficiency of the system is reduced. Further, with conventional transducers, the possibility is present that blind spots will exist in the room where few vibrational energy paths will exist. The effectiveness of such a system in detecting motion in such areas would be minimized.

It is therefore a principal object of the present invention to provide an improved vibration transducer particularly adapted for use in a motion detecting system.

More particularly, it is an important object of this invention to provide a transducer of the magnetostrictive type having high sensitivity and efficiency.

Another object of this invention is to provide an improved magnetostriction transducer wherein the magnetostriction effect is maximized.

Other and further objects, features and advantages of the present invention will become apparent from a reading of the following description.

A transducer constructed in accordance with the invention comprises a coil, a rod of magnetostrictive material located within the coil, and resonating means mechanically coupled to the rod and having a predetermined natural frequency of vibration, the rod and the

resonating means forming a vibrating system having a natural frequency of vibration substantially equal to the predetermined frequency. In accordance with a further feature of the invention, the resonating means may be realized as two cylindrical elements each affixed adjacent the mid point thereof to a respective end of the magnetostrictive rod. The magnetostrictive rod of the invention may comprise a plurality of laminae insulated from each other by means of thin strips of paper or the like, the outer two laminae being channel-shaped with the flanges thereof extending outwardly to minimize transverse bending of the rod due to transverse magnetostrictive forces set up therein by the alternating current flowing in the coil.

The invention will now be described in greater detail with reference to the appended drawings, in which:

Fig. 1 is a plan or top view of a transducer constructed in accordance with the present invention and mounted on a vertical supporting member;

Fig. 2 is a front elevational view thereof with the cover plate removed;

Fig. 3 is a sectional view taken along the line 3—3 of Fig. 2;

Fig. 4 is a sectional view taken along the line 4—4 of Fig. 2; and

Fig. 5 is an end view of the coil spool showing the mounting screws for the magnetostriction rod.

Referring now to the drawings, there is illustrated a preferred embodiment of a transducer constructed in accordance with the present invention. The principal elements of the transducer are a reflector 10, a magnetostriction rod 11, a coil assembly generally designated by the reference numeral 12, and a pair of cylindrical resonating elements 13 and 14.

The reflector 10 comprises a central flat portion 15 and curved end portions 16 and 17 adapted to reflect outwardly vibrational energy emanating from the resonators 13 and 14 or to direct toward the resonators received vibrational energy. The reflector 10 may conveniently be affixed to a supporting member or wall 18 by screws 19. A generally rectangular housing 20 is affixed to the central portion 15 of the reflector 10 by means of screws 21. The screws 21 also serve to affix a channel-shaped bracket member 22 to the rear of the housing 20. Brackets 23 and 24, which may be affixed to diagonally opposite corners of the housing 20 by any suitable means such as welding, are provided with threaded holes 25 and 26, respectively, adapted to receive screws 28 and 29, respectively, for affixing a cover plate 30 to the housing 20.

Side members 31 and 32 of the housing 20 are provided with elongated slots 33 adapted to accommodate the coil assembly 12. The coil assembly 12 comprises a cylindrical spool or former 34 which may be made of any suitable insulating material such as, for example, polystyrene. Each end of the spool 34 is provided with flattened opposite outer surfaces 35, as shown in Fig. 5, which are adapted to be engaged by the edges of the slots 33 to securely maintain the coil assembly 12 in place and to prevent the latter from turning. A bushing 36, which may conveniently be made of nylon or the like, is located within the spool 34 at the center thereof to lend support to the coil assembly and to provide a secure mounting for the magnetostriction rod, as will be apparent from the discussion hereinafter. A wire coil 37 is wound on the spool 34 in two sections, leaving a bare space around the outer periphery of the spool at the center thereof, and similar bare spaces at the ends of the spool. The bare area at the center of the spool is provided with four tapped holes equidistantly spaced and adapted to receive set screws 38 which pass through correspondingly located holes in the bushing 36. The screws 38 serve to position the magnetostriction rod 11 within the coil assembly

coincident with the axis thereof. For this purpose the screws 38 contact the respective surfaces of the rod 11, preferably at the mid point thereof.

The ends of the coil 37 are connected to respective terminals 39 and 40. The terminals 39 and 40 are fastened to a terminal block 41 by means of screws 42 and 43, respectively. The screws 42 and 43 also serve to connect input leads 44 and 45 to the respective terminals 39 and 40. In a transmitting transducer the input leads 44 and 45 will be connected to a source of alternating current having the desired frequency, which might be, for example, 22,000 cycles. In a receiving transducer, the leads 44 and 45 will serve as the output leads to supply to suitable detecting or other equipment the alternating current generated in the coil 37 by mechanical vibrations of the rod 11. The block 41 is affixed to the housing 20 by means of screws 46 and 47. The screw 46 may conveniently be employed to afford a ground connection for the input lead 44, as shown in Fig. 2.

The magnetostriction rod 11 comprises a plurality of laminae of nickel or other suitable magnetostriction material separated by sheets of wax paper or other suitable insulating material. As is best shown in Fig. 4, the outer laminae 48 and 49 are channel-shaped in order to minimize the magnetostriction effect transversely of the rod. This construction of the outer laminae provides stiffness to minimize or eliminate transverse bending of the rod 11 in operation. Magnetostriction rods or bars are generally held together by gluing or shellacking the laminae. Either method produces a solid piece which must change dimensions as a unit. In such an arrangement energy may be wasted and longitudinal dimensional change may be limited by the requirement that energy must be expended in overcoming the longitudinal cohesive forces of the binding material. In accordance with the invention, the laminae are preferably not bound together by cohesive material but are separated by a smooth insulating material. As is best shown in Fig. 3, the upturned edges of the channeled laminae 48 and 49 extend at each end to a point just short of the end of the rod 11. Cap members 50 and 51 are provided at each end of the rod 11 and may, if desired, be soldered or otherwise rigidly affixed thereto.

The cylindrical resonators 13 and 14, which may conveniently be made in the form of thin-walled, wide diameter tubes, are each provided with a longitudinally centered hole adapted to receive rivets 52 and 53, respectively. The other ends of the rivets are mounted in the ends of the caps 50 and 51, respectively, so that the tubes 13 and 14 are rigidly secured to the caps 50 and 51, respectively, and hence to respective ends of the magnetostriction rod 11.

The transmitting transducer of the invention operates on the well-known magnetostriction principle that, when a ferromagnetic material is placed in a varying magnetic field, certain changes occur in its internal structure and the resulting stresses on the specimen will cause small changes in its physical dimensions. The receiving transducer of the invention operates on the converse of this principle that, when the material in the presence of a magnetic field is subjected to external stress, its degree of magnetization is altered. The mechanical changes caused by variation in the induced magnetic field may be in the linear dimensions, the circular dimensions, or in the volume. The effect, however, is more pronounced in the linear dimensions of the specimen, the change of length being either in a positive (increasing) or negative (decreasing) direction, depending upon the magnetostrictive coefficient of the material used.

In the embodiment of the invention illustrated in the drawings, the magnetostriction rod 11 has been described as made up of thin strips of nickel held together by cap members 50 and 51 and separated by thin strips of an insulating material such as paper. When the magnetostriction rod 11 is made of nickel, as described, the nega-

tive magnetostrictive coefficient of nickel will tend to cause the rod to contract and return to its normal length twice during each cycle of magnetization. While somewhat less efficient than nickel, Monel metal, which has a positive magnetostrictive coefficient, could be used for the rod 11. Other magnetostrictive materials could be used, if desired. Since the magnetostrictive effect is independent of the direction of the applied magnetic field, a permanent magnetic field may be employed to exert a steady polarizing effect on the rod 11. When the magnitude of this polarizing field is approximately equal to the amplitude of the induced magnetic flux, both the mechanical and electrical frequencies will be identical. Otherwise, the mechanical frequency would be double the electrical frequency. A permanent bar magnet 54 held against the rear of the housing 20 by the channel member 22 may conveniently be employed to secure the desired polarizing field.

The resonators 13 and 14, which may conveniently be made of aluminum, should be dimensioned so that their fundamental frequency of vibration will coincide with the fundamental frequency of the alternating current supplied to the coil 37 through the conductors 44 and 45 or received from another transducer. Similarly, the length of the rod 11 should be chosen so that its fundamental frequency of vibration is approximately equal to that of the desired operating frequency, i. e., the frequency of the current supplied to the coil 37 or the vibrational frequency of received energy. The large vibrating surface offered by the resonators 13 and 14 is very great compared to the cross-sectional area at each end of the rod 11, so that these resonators accordingly enhance the efficiency of the unit for transmission of sound waves in air. Similarly, when the transducer is used for receiving sound vibrations, the large vibrating surface area offered by the resonators 13 and 14 will tend to maximize the fundamental frequency alternating current voltage induced in the coil 37 and supplied as an output to the conductors 44 and 45. The magnitude of the output voltage is proportional to the amplitude of vibration of the rod 11 and hence to the amplitude of vibration of the resonators 13 and 14.

In general, it may be said that the rod 11 should be given a length approximately equal to an integral number of half-wave lengths at the operating frequency, while the rod 11 should be supported at a nodal point thereof. The nodal points will occur at odd quarter-wave lengths from the ends of the rod 11, and the nodal point selected for support is preferably at the mid point of the rod. The half and quarter-wave lengths referred to are those of the sound energy in air. In practice, the rod 11 may be made slightly less than an integral number of half-wave lengths long so that the rod 11 together with the resonators 13 and 14 will form a system having a natural frequency of vibration substantially equal to the operating frequency. In addition to this system resonance, the resonators 13 and 14 should each have a natural frequency of vibration substantially equal to the operating frequency. The shortening of the rod 11 is desirable since, while the resonators 13 and 14 are very light, their mass does have some effect on the natural period of the system. The theoretical length of the resonators 13 and 14, which will cause the same to be resonant at the operating frequency, may be calculated from the following formula:

$$f_1 = \frac{1.133 \frac{L}{P}}{L^2 \sqrt{E \frac{K^2}{P}}}$$

Where f_1 is the fundamental frequency of operation, L is the theoretical axial length of each resonator, E is Young's modulus, K is the radius of gyration, and P is

the density of the material of which the resonator is formed. The radius of gyration K is equal to

$$\sqrt{\frac{a^2 a_1^2}{2}}$$

where a is the outside radius of the cylinder and a_1 is the inside radius thereof. The actual length required will be somewhat less than the theoretical length because of the effect on natural frequency produced by the connection to the end of the rod 11. It will generally be found advisable in each case to empirically determine the requisite shortening from the theoretical length.

In a transmitting transducer considerable heat will be generated in operation which will to some extent vary the natural frequencies of the rod 11 and resonators 13 and 14. The dimensions of these elements should therefore be selected so that the natural frequencies under actual operating conditions will coincide with the frequency of the applied alternating potential. In a receiving transducer these heating effects will generally be negligible, so that the design thereof will not have to take into account dimensional changes due to temperature rise.

When used as a receiving transducer in a motion detecting system, vibrations received by the transducer having a frequency slightly different from that of the fundamental operating frequency will cause vibrations of the resonators 13 and 14 and of the rod 11 to occur at this different frequency, thereby inducing an alternating current component of like frequency in the coil 37. Suitable detecting apparatus may be connected to the conductors 44 and 45 to provide a desired indication of the reception of a frequency different from that of the fundamental frequency.

While the invention has been described in connection with a specific embodiment thereof and in a specific use, various modifications thereof will occur to those skilled in the art without departing from the spirit and scope of the invention as set forth in the appended claims.

What is claimed is:

1. In a motion detection system employing sound waves having a given frequency, a transducer comprising a coil, a rod of magnetostrictive material located within said coil, and cylindrical resonating means mechanically coupled to said rod and having a predetermined natural frequency of vibration substantially equal to said given frequency, said rod and said resonating means forming a vibrating system having a natural frequency of vibration substantially equal to said given frequency.

2. A transducer, comprising a coil, a rod of magnetostrictive material located within said coil, and cylindrical resonating means mechanically coupled to said rod and having a predetermined natural frequency of vibration, said rod and said resonating means forming a vibrating system having a natural frequency of vibration substantially equal to said predetermined frequency.

3. A transducer, comprising a coil, a rod of magnetostrictive material located within said coil, and a pair of cylindrical elements each affixed to said rod at a respective end thereof and each having a predetermined natural frequency of vibration, said rod and said resonating elements forming a vibrating system having a natural frequency of vibration substantially equal to said predetermined frequency.

4. A transducer, comprising a coil, a rod of magnetostrictive material adapted to have longitudinal mechanical vibrations of given frequency set up therein, means to support said rod within said coil at a nodal point of the rod with respect to vibrations of said given frequency, and a pair of cylindrical resonating elements each connected adjacent the mid point thereof to a respective end of said rod whereby like frequency mechanical vibrations occur in said resonating elements and in said rod, said rod and said resonating elements forming a vibratory system having a natural frequency of vibration substantially equal to said given frequency and said resonat-

ing elements each having a natural frequency of vibration substantially equal to said given frequency.

5. A transducer, comprising a coil, a rod of magnetostrictive material magnetically coupled to said coil and adapted to have longitudinal mechanical vibrations of given frequency set up therein, means to subject said rod to a polarizing magnetic field, means to support said rod within said coil at a nodal point of the rod with respect to vibrations of said given frequency, and a pair of cylindrical resonating elements each connected adjacent the mid point thereof to a respective end of said rod whereby like frequency mechanical vibrations occur in said resonating elements and in said rod, the axes of said resonating elements being transverse to the axis of said rod, said rod and said resonating elements forming a vibratory system having a natural frequency of vibration substantially equal to said given frequency and said resonating elements each having a natural frequency of vibration substantially equal to said given frequency.

6. A transducer, comprising a coil adapted to have an alternating current passed therethrough, a rod of magnetostrictive material, means to support said rod within said coil whereby the varying magnetic field produced by alternating current flow in said coil produces longitudinal mechanical vibrations of given frequency in said rod, and a pair of cylindrical resonating elements each connected adjacent the mid point thereof to a respective end of said rod whereby like frequency mechanical vibrations occur in said resonating elements and in said rod, the axes of said resonating elements being transverse to the axis of said rod, said rod and said resonating elements forming a vibratory system having a natural frequency of vibration substantially equal to said given frequency and said resonating elements each having a natural frequency of vibration substantially equal to said given frequency.

7. A transducer, comprising a coil adapted to have an alternating current of given frequency passed therethrough, a rod of magnetostrictive material, means to subject said rod to a polarizing magnetic field, means to support said rod within said coil at a mid point thereof whereby the varying magnetic field produced by the alternating current flow in said coil produces longitudinal mechanical vibrations of said given frequency in said rod, and a pair of cylindrical resonating elements each connected adjacent the mid point thereof to a respective end of said rod whereby like frequency mechanical vibrations occur in said resonating elements and in said rod, the axes of said resonating elements being transverse to the axis of said rod, said rod and said resonating elements forming a vibratory system having a natural frequency of vibration substantially equal to said given frequency and said resonating elements each having a natural frequency of vibration substantially equal to said given frequency.

8. A transducer, comprising a coil, a rod of magnetostrictive material adapted to have longitudinal mechanical vibrations of given frequency set up therein, said rod comprising a plurality of laminae insulated from each other and having the two outer opposite laminae channel-shaped with the flanges extending outwardly to minimize transverse bending of the rod due to transverse magnetostrictive forces set up therein, means to support said rod within said coil at a nodal point with respect to said given frequency, and a pair of cylindrical resonating elements each connected adjacent the mid point thereof to a respective end of said rod whereby like frequency mechanical vibrations occur in said resonating elements and in said rod.

9. A transducer, comprising a coil, a laminated rod of magnetostrictive material adapted to have longitudinal mechanical vibrations of given frequency set up therein, said rod having a length slightly less than an integral number of half-wave lengths at said given frequency, means to support said rod within said coil at a nodal point of said rod with respect to vibrations of said given frequency.

quency, and a pair of cylindrical resonating elements each connected to a respective end of said rod whereby like frequency mechanical vibrations occur in said resonating elements and in said rod, said resonating elements each having a natural frequency of vibration substantially equal to said given frequency.

10. In a vibration transducer having a coil, a magnetostriction rod located within the coil and comprising a plurality of laminae insulated from each other, the outer opposite two laminae being channel-shaped with the flanges thereof extending outwardly to minimize transverse bending of the rod due to transverse magnetostrictive forces set up therein by alternating current flowing in said coil.

11. In a vibration transducer having a coil, a magnetostriction rod located within the coil and comprising a plurality of laminae, and a plurality of thin, smooth insulating members separating adjacent laminae, the outer opposite two laminae being channel-shaped with the flanges thereof extending outwardly to minimize transverse bending of the rod due to transverse magnetostrictive forces set up therein by alternating current flowing in said coil.

12. A transducer, comprising a coil, a laminated rod of magnetostrictive material adapted to have longitudinal

mechanical vibrations of given frequency set up therein, said rod having a length slightly less than an integral number of half-wave lengths at said given frequency, means to support said rod within said coil at a nodal point of said rod with respect to vibrations of said given frequency, a pair of cylindrical resonating elements, means to connect each of said resonating elements to a respective end of said rod whereby like frequency mechanical vibrations occur in said resonating elements and in said rod, said resonating elements each having a natural frequency of vibration substantially equal to said given frequency and said securing means providing a substantial point contact between the resonating elements and the respective ends of said rod, and a curved reflector spaced from said resonating elements to direct vibrational waves.
